S. B. HENSHAW,
MEANS FOR FILLING GLASS MELTING TANKS.
APPLICATION FILED AUG. 28, 1920.

1,409,716.

Patented Mar. 14, 1922.

UNITED STATES PATENT OFFICE.

SETH B. HENSHAW, OF CHARLESTON, WEST VIRGINIA, ASSIGNOR TO THE LIBBEY-
OWENS SHEET GLASS COMPANY, OF TOLEDO, OHIO, A CORPORATION OF OHIO.

MEANS FOR FILLING GLASS-MELTING TANKS.

1,409,716.

Specification of Letters Patent. Patented Mar. 14, 1922.

Application filed August 28, 1920. Serial No. 406,576.

To all whom it may concern:

Be it known that I, SETH B. HENSHAW, a citizen of the United States, residing at Charleston, in the county of Kanawha and State of West Virginia, have invented new and useful Improvements in Means for Filling Glass-Melting Tanks, of which the following is a specification.

This invention relates to the art of glass making, and is concerned particularly with a device for easily and expeditiously filling a glass melting tank with cullet, when the furnace is first started in operation, or when the furnace or tank is being refilled after having been closed down and emptied for repairs or other reasons.

One object of the invention is to provide a device which is readily attached to any furnace, and easily removable so that a single filling device will suffice for a battery of furnaces or melting tanks, as it is extremely unlikely that its use would be required with more than one tank of a battery at a time.

A further object is to provide a closure means for the tank, cooperating with the filling device to close the tank opening and retain as much heat as possible therein while the filling device is not in operation and be automatically moved to uncover the filling opening when the filling device is moved up to discharging position.

Further objects and advantages of the invention will become apparent as the detailed description of the apparatus proceeds.

Referring to the accompanying drawings:

Fig. 1 is a side elevation of the device forming the subject matter of this invention, the receiving end of the glass tank and the building floor being shown in vertical section.

Fig. 2 is a fragmental side elevation, similar to Fig. 1, showing the hopper or filling device in discharging position.

Fig. 3 shows a plan view of the hopper.

Fig. 4 is a view of the sliding closure and its trackway, taken from below, looking in the direction of the arrow *a* in Fig. 1.

Fig. 5 is a diagram showing one way of arranging the hoisting cables for the hopper.

The "dog house" 1 of the melting tank 2 ordinarily has its upper portion open at 3

so that the glass producing batch can be fed into the tank through batch pipe 4. This pipe connects with a supply hopper at its upper end, and at its lower end is provided with a pivoted closure 5, operable by lever 6, for regulating the flow of batch into the tank. In the normal operation of the furnace, when filled with glass to the required level, the batch will be heaped up at the filling opening 3 so as to close the opening and prevent the undue escape of heat from the tank. All of the above is old structure, now in common use, and is not claimed as part of this invention.

When the tank is empty and it is desired to refill the tank and heat up the furnace, the slab 7 is placed over the upper portion of opening 3, and the movable clay block closure 8 is mounted in position to close the side portion of the filling opening, as shown in Fig. 1. This clay block 8 is mounted in a frame or carriage 9 provided with rollers 10 which move in trackways 11, formed of suitable channel bars, all as shown more particularly in Fig. 4. The trackways 11 are suspended by means of brackets 12 from the batch pipe 4, as shown in Figs. 1 and 2. A cable 13 running over pulley 14, connects the carriage 9 with a counterweight 15, the weight of the clay block closure 8 being sufficient to elevate the counterweight, so that the closure will ordinarily move down to closed position as shown in Fig. 1.

The filling device or hopper 16, is of substantially the form shown in Figs. 1 and 3, having a cullet holding chamber or trough surrounded on three sides by the walls 17, and having at its fourth side an outwardly extending spout 18, through which the cullet is discharged. The hopper is mounted at a slight angle, as shown in Fig. 1, in a frame 19, of suitable angle-irons. One end of the frame 19 is pivoted on a shaft 20 mounted in bearings 21, removably bolted to the floor, or other framework adjacent to the tank. The elevated end of hopper 16, which is provided with the spout, overhangs the pivot-shaft or axis of the frame as shown in Fig. 1. The rear end of the hopper, remote from the axis 20, is adapted to be elevated by any suitable mechanism, to discharge the contents of the hopper through spout 18 into the tank. In practice a suitable cable and wind-

lass hoisting mechanism is preferable for this purpose, and may be arranged as shown more clearly in the diagram of Fig. 5. The cable 22 is attached at one end 23 to the buckstay 24 of the furnace or any other convenient stationary object, then passes down and around a pulley 25 at one outer corner of the hopper, then up and over pulleys 26 and 27, down and around pulley 28, at the other outer corner of the hopper, up and over pulley 29, and thence to the winding drum of any well-known type of windlass (not known).

For automatically operating the closure 8, another cable 30 is secured at one end 31 to the lower side of the frame 19, and after passing around pulleys 32 and 33, shown in the drawings as mounted below floor 34 is attached to the counterweight 15 at 35.

In operation, the cullet is brought up in any suitable truck or other conveyor and dumped into the hopper 16. When the hopper is filled, the windlass is operated to swing the hopper about its pivot into discharging position. As the hopper moves up away from the floor, it pulls up on cable 30, drawing down the counterweight 15, which through cable 13 pulls the clay block 8 up the trackways 11, uncovering the filling opening, and allowing spout 18 to project into the opening and discharge the contents of the hopper into the tank, all as shown in Fig. 2 of the drawings. When the hopper is emptied it is lowered back onto the floor, at the same time permitting the closure 8 to run back down trackways 11 until it resumes its first position closing opening 3.

It is seen that this mechanism is easily and quickly operable, requires little attention, and does not leave the filling opening of the tank uncovered unnecessarily, thus retaining as much of the heat as possible in the tank, and facilitating the firing up of a new furnace, or the returning of an old one to active duty.

It is apparent that many changes could be made in the form and details of this device and its operating mechanism without departing from the scope of the invention as outlined by the following claims.

Claims:

1. In an apparatus for filling glass melting tanks, a hopper adapted to be mounted adjacent the filling opening of the tank, means for moving the hopper to discharging position within the opening, a closure for the opening, and interconnecting means between the closure and hopper, so that one of them is moved into the opening when the other is moved away.
2. In an apparatus for filling glass melting tanks, a tiltable hopper adapted to be pivoted adjacent the filling opening of the tank, means for tilting the hopper to discharging position, a closure or gate for the
3. An auxiliary filling device for glass melting tanks comprising a hopper adapted to be mounted adjacent the filling opening of the tank, a closure for the filling opening, and means for simultaneously moving the hopper to discharging position within the opening and withdrawing the closure from the opening, the closure automatically returning to closing position when the hopper is withdrawn after being discharged.
4. In an apparatus for filling glass melting tanks, a hopper adapted to be mounted adjacent the filling opening of the tank, means for moving the hopper to discharge its contents into the tank, a closure for the filling opening, a trackway along which the closure is movable to and from closing position, and connections between the closure and hopper for withdrawing the closure from the opening when the hopper is moved into the filling opening to discharge its contents.
5. In an apparatus for filling glass melting tanks, a tiltable hopper adapted to be mounted adjacent the filling opening of the tank, means for tilting the hopper to discharge its contents into the tank, a closure for the filling opening, a slideway for the closure along which it is movable to and from closing position, a counterweight for the closure, a cable connecting the closure and counterweight, and a cable connecting the counterweight and hopper, whereby when the hopper is raised to discharging position the counterweight will be drawn down and the closure moved back along its slideway to allow the contents of the hopper to enter the filling opening.
6. In an apparatus for filling glass melting tanks, a tiltable hopper adapted to be mounted adjacent the filling opening of the tank, means for tilting the hopper to discharge its contents into the tank, a closure for the filling opening, a slideway for the closure along which it is movable to and from closing position, a counterweight for the closure, a cable connecting the closure and counterweight, and a cable connecting the counterweight and hopper, whereby when the hopper is raised to discharging position the counterweight will be lowered and the closure moved back along its slideway to uncover the filling opening, the closure returning to closing position by its own weight when the hopper is moved away from the opening.
7. An auxiliary filling device for glass melting tanks, comprising a normally horizontal frame pivotally mounted at one end adjacent the filling opening of the tank, a

filling opening, and means connecting the hopper and closure so that the closure will be automatically withdrawn from the opening when the hopper is tilted to discharging position.

70

3. An auxiliary filling device for glass melting tanks comprising a hopper adapted to be mounted adjacent the filling opening of the tank, a closure for the filling opening, and means for simultaneously moving the hopper to discharging position within the opening and withdrawing the closure from the opening, the closure automatically returning to closing position when the hopper is withdrawn after being discharged.

80

4. In an apparatus for filling glass melting tanks, a hopper adapted to be mounted adjacent the filling opening of the tank, means for moving the hopper to discharge its contents into the tank, a closure for the filling opening, a trackway along which the closure is movable to and from closing position, and connections between the closure and hopper for withdrawing the closure from the opening when the hopper is moved into the filling opening to discharge its contents.

85

5. In an apparatus for filling glass melting tanks, a tiltable hopper adapted to be mounted adjacent the filling opening of the tank, means for tilting the hopper to discharge its contents into the tank, a closure for the filling opening, a slideway for the closure along which it is movable to and from closing position, a counterweight for the closure, a cable connecting the closure and counterweight, and a cable connecting the counterweight and hopper, whereby when the hopper is raised to discharging position the counterweight will be drawn down and the closure moved back along its slideway to allow the contents of the hopper to enter the filling opening.

90

6. In an apparatus for filling glass melting tanks, a tiltable hopper adapted to be mounted adjacent the filling opening of the tank, means for tilting the hopper to discharge its contents into the tank, a closure for the filling opening, a slideway for the closure along which it is movable to and from closing position, a counterweight for the closure, a cable connecting the closure and counterweight, and a cable connecting the counterweight and hopper, whereby when the hopper is raised to discharging position the counterweight will be lowered and the closure moved back along its slideway to uncover the filling opening, the closure returning to closing position by its own weight when the hopper is moved away from the opening.

100

7. An auxiliary filling device for glass melting tanks, comprising a normally horizontal frame pivotally mounted at one end adjacent the filling opening of the tank, a

105

normally inclined trough or hopper fixedly secured to the frame with its lower closed end at that end of the frame remote from the pivot, and with the upper open end or 5 spout overhanging the pivot, and means for swinging the frame and hopper about the pivot so that the spout will be projected into

the filling opening and the hopper discharged into the tank.

Signed at Charleston, in the county of 10 Kanawha and State of West Virginia, this 20th day of August, 1920.

SETH B. HENSHAW.
